UNITED STATES PATENT OFFICE

HUGO G. RASSMANN, OF BEAVER DAM, WISCONSIN, ASSIGNOR TO F. RASSMANN
MANUFACTURING COMPANY, OF BEAVER DAM, WISCONSIN

STALL OR STANCHION

Application filed March 5, 1930. Serial No. 433,342.

This invention relates to improvements in stalls or stanchions of the type employed to hold the heads of cattle while they are stabled in the barn.

Heretofore it has been proposed to arrange the stanchions in series and to provide a common operating means for opening and closing all of the stanchions. In one such proposal, a sliding bar forming part of the operating mechanism, is positioned above the top rail of the stalls, and this not only adds to the height of the structure, but necessitates the use of special bearings for the sliding bar, positioned above said top rail. As the top rail is supported by vertical posts, I have devised a construction by which the sliding bar may not only be arranged beneath the top rail, but may be guided by the clamps which connect the posts to the top rail, and in these clamps, protected anti-friction bearings may be arranged for the actuating bar, the construction being such as to prevent hay, chaff or the like from entering the clamps and interfering with the operation of the roller bearings.

Therefore, one of the objects of the present invention is to provide a stall of this character, in which certain of the clamps not only join the top rail to the vertical posts, but also function as anti-friction guides for the actuating rod of the stanchions.

Another object is to furnish a structure of this type in which the hinged members of the stanchions are connected to the sliding operating bar by means of novel latches, so that one or more cows may be held by their stanchions while the other cows are released, and vice versa.

A further object is to provide in such a mechanism, special latches for positively securing the hinged members of the stanchions to the fixed members of the latter, so that any one of said hinged members may be locked in closed position when desired.

With the foregoing objects outlined and with other objects in view which will appear as the description proceeds, the invention consists in the novel features hereinafter described in detail, illustrated in the accom-

panying drawings, and more particularly pointed out in the appended claims.

Referring to the drawings,

Fig. 1 is a front elevation of stalls and stanchions provided with the improvements. 55

Fig. 2 is an enlarged front elevation of one of the guide clamps, partly in section.

Fig. 3 is a sectional view on the line 3—3 of Fig. 2.

Fig. 4 is an end elevation of one of the latch devices partly in section, and showing the latch closed. 60

Fig. 5 is a similar view but showing the latch held opened by its keeper.

Fig. 6 is a front elevation of one of the 65 latch devices.

Fig. 7 is a horizontal sectional view on the line 7—7 of Fig. 4.

In the drawings, 10 designates the foundation beam of the stalls in which the lower 70 ends of the vertical posts 11 are mounted; these posts being additionally supported by means of the usual partition pipes 12.

Arranged at the tops of the posts, and supported by the latter are special clamps 13, 75 each preferably consisting of a pair of plates or special castings 14 and 15, (Figs. 2 and 3), secured together by any suitable fastening means such as bolts 16, 17, 18, 19 and 20. Vertically disposed semi-circular recesses in 80 the lower ends of the plates, provide cylindrical bores to receive the cylindrical upper ends of the posts 11, and the bolts 16 and 17 function to firmly secure the clamp to the upper ends of the posts. 85

The clamp plates are also provided with horizontally disposed semi-cylindrical recesses which provide a horizontal bore to receive the top rail 21 of the stalls, and the bolts 19 and 20 act to firmly secure the clamp 90 to the top rail.

Intermediate the ends of the clamp plates, other horizontally disposed semi-cylindrical recesses are provided which form a horizontal bore 22 that serves as a guide for the sliding 95 operating rod 23, and to permit the rod to slide without friction, a grooved roller 24 is rotatably mounted in the clamp on the bolt 18. At this point it will be noted that the roller is positioned midway between the side 100

edges of the clamp, so that it is spaced some distance from the ends of the bore 22, and this arrangement will act to prevent any hay, chaff or the like from working itself into the 5 clamp and interfering with the rotation of the roller.

Swivel supports 25 are securely clamped to the top rail between the special clamps 13, and the sliding bar 23 also slides through 10 guide bores in these swivel supports.

An actuating handle 26 for the sliding bar is pivotally mounted upon the bolt 18 of one of the special clamps, and its intermediate portion is pivotally connected at 27 to one 15 end of a pitman 28, whose other end is pivotally connected at 29 to the sliding bar 23. Obviously, when the lever is swung on its pivot 18, the sliding bar will be shifted in one direction or the other.

20 Movable sure stop rods 30 are pivotally connected at 31 to the sliding bar, and their lower ends engage eyes in brackets 32 which are secured on the posts 11. In actual practice, stationary sure stop rods 33 are also 25 mounted on these posts.

The fixed members 34 of the stanchions are suspended by swivels 35 from the swivel supports 25, and they are joined by chains 36 to the foundation beam, while the movable 30 members 37 of the stanchions are pivotally connected to the fixed members by means of hinges 38. The upper end of each of the movable members is provided with a bracket or swivel 39 which slides along the horizontal 35 portion 40 of the fixed member, and each of these swivels has an upwardly extending finger 41 that is latched to a special latch 42 and provided with a head 41^a. This latch (Figs. 4 to 7 inclusive), also preferably 40 consists of a pair of clamp plates 43 and 44 having horizontal recesses forming a horizontal bore to receive the sliding bar 23, and the latch plates are clamped to the sliding bar by any suitable means, such as bolts 45 45 and 46. If desired, the plates may have extensions to form a guide 47 to slidably engage the top rail of the stalls.

One of the clamp plates is provided with laterally projecting ears 49 which carry a pivot 50 or pin 50 on which an angular fork 51 is pivotally mounted; this fork having tines 52 that are adapted to prevent forward or backward movement of the finger 41. The clamp plates have depending lugs 53 which prohibit lateral 55 movement of the finger 41 and prevent dropping of the head 41^a; and when the latch is secured to the finger 41, the tines pass along opposite sides of the lugs 53, so that the tines and lugs provide a box or enclosure to receive the finger. When the latch is closed, it 60 is held in this position by a sliding keeper 55, which has a vertically disposed slot 56 to receive one of the bolts of the clamp, and between the head of this bolt and the keeper, 65 a washer 57 is arranged, so as to prevent the

keeper from disengaging its guide boss. A lug 59 on the keeper serves as a finger-piece to permit the operator to actuate the keeper, and also cooperates with a bar 60 of the latching fork, so as to hold the tines in inoperative 70 position (Fig. 5), when the finger 41 of the swivel is to be disconnected from the latch. At such a time, a pivoted latch 61, (Fig. 1), mounted at the upper end of the movable member of the stanchion, can be engaged 75 with a projecting pin 62 on the stationary member of the stanchion so as to lock the stanchion against opening.

From the foregoing it will be seen that my invention enables the slidable actuating bar 80 23 to be arranged below the top rail of the stall, and to be guided by the clamps that couple the supporting post to the top rail. Furthermore, my construction allows any one of the movable members of the stanchions to be latched to, or disconnected from the actuating bar, so that one or more of the cows 85 may be retained by their stanchions, while the remainder of the cows are released by the actuation of a common hand control.

90 While I have disclosed what I now consider to be a preferred embodiment of the invention in such manner that the same may be readily understood by those skilled in the art, I am aware that changes may be made in the details disclosed without departing from the 95 spirit of the invention, as expressed in the claims.

What I claim and desire to secure by Letters Patent is:

1. In combination, stalls including vertical posts, a top rail, and clamps joining the posts to the top rail, stanchions having movable members, means for operating said movable members comprising a bar arranged beneath the top rail and slidably mounted in said clamps and connected to said movable members, and anti-friction bearings for the rod arranged within said clamps.

110 2. In combination, stalls including vertical posts, a top rail, and clamps joining the posts to the top rail, stanchions having movable members, and means for operating said movable members, comprising a bar arranged beneath the top rail and slidably mounted in said clamps and connected to said movable members, each of said clamps being formed of a plurality of sections shaped to provide bores to receive the top rail, the sliding bar and an end of one of the posts.

115 3. In a structure of the character described, a stanchion having a movable member provided with a projecting finger, an operating rod, a latch carried by the operating rod and engaging said finger, and a keeper 120 cooperating with said latch and adapted to hold the latch in either open or closed position.

4. In a structure of the character described, a stanchion having a movable member provided with a projecting part, an op- 130

erating member, a bracket fixedly secured to the operating member and having a runway to receive said protecting part, and a forked latch structure carried by the bracket and engaging said projecting part to prevent the latter from leaving said runway.

5. In a structure of the character described, a stanchion having a movable member provided with a projecting part, an operating member, a bracket fixedly secured to the operating member, and a latch structure carried by the bracket and engaging said projecting part, said latch structure including projecting lugs and cooperating fork tines to form an enclosure about said projecting part.

6. In a structure of the character described, a stanchion having a movable member provided with a projecting part, an operating member, a bracket fixedly secured to the operating member and having a runway to receive said protecting part, a latch structure carried by the bracket and engaging said projecting part to prevent the latter from leaving said runway, and a sliding keeper for the latch structure slidably mounted on said bracket.

7. In a structure of the character described, a stanchion having a movable member provided with a projecting part, an operating member, a bracket fixedly secured to the operating member, a latch structure carried by the bracket and engaging said projecting part, and a sliding keeper for the latch structure slidably mounted on said bracket, said keeper having a finger-piece designed to hold the latch structure in open position.

8. In a structure of the character described, a stanchion including a movable member provided with a projecting finger, an operating bar, a bracket mounted on said bar and having projecting lugs to engage said finger, and a latch pivotally mounted on the bracket and having tines adapted to straddle said lugs and to also engage said finger.

9. In a structure of the character described, a stanchion including a movable member provided with a projecting finger, an operating bar, a bracket mounted on said bar and having projecting lugs to engage said finger, a latch pivotally mounted on the bracket and having tines adapted to straddle said lugs and to also engage said finger, and a keeper for the latch slidably mounted on said bracket.

10. In a structure of the character described, a stanchion including a movable member provided with a projecting finger, an operating bar, a bracket mounted on said bar and having projecting lugs to engage said finger, a latch pivotally mounted on the bracket and having tines adapted to straddle said lugs and to also engage said finger, and a keeper for the latch slidably mounted on

said bracket, said keeper having a finger-piece designed to hold the latch in open position.

In testimony whereof, I have signed this specification.

HUGO C. RASSMANN.
